UNITED STATES PATENT OFFICE

ALBERT W. W. VAN HOORN, OF WILMINGTON, DELAWARE, ASSIGNOR TO AMERICAN CAR AND FOUNDRY COMPANY, OF NEW YORK, N. Y., A CORPORATION OF NEW JERSEY

MUFFLER

Application filed November 22, 1929. Serial No. 409,034.

This invention relates to exhaust mufflers for use with hydrocarbon engines and has for one object the provision of a simple, cheap and effective device that can be readily constructed of cast metal to provide a device which may be easily assembled and disassembled.

Another object of the invention is the provision of a muffler for internal combustion engines, which is formed of a number of identical or similar castings detachably connected together.

Still another object of this invention is the provision of a muffler which is so constructed as to reduce back pressure on the engine to a minimum.

A further object of the invention is the provision of a muffler particularly adapted for use with marine engines in which backflow of water is prevented.

A still further object of this invention is the provision of a muffler for marine engines which is so formed as to retain therein a quantity of water sufficient to insure proper cooling and muffling or sound reduction of the exhaust gases.

Other objects and advantages of this invention will be apparent from the following description taken in conjunction with the accompanying drawings, in which:

Figure 1 is a sectional view of the muffler; the view being taken on the line 1—1 Figure 2;

Fig. 2 is a sectional view of the muffler taken on the line 2—2 Figure 1;

Fig. 3 is an end view of the muffler shown in the preceding figures, the view being that of the left-hand end of Figure 2; and

Fig. 4 is an end view taken at the right of Figure 2, certain parts being broken away to show the interior of the muffler.

Referring now more particularly to the drawings, the muffler of the present invention is in general, a substantially hollow casting (rectangular in the instance shown) composed of two identical castings A and B which for convenience are termed upper and lower muffler sections respectively.

Each muffler section comprises a shell or body having a top 2, side walls 4, ends 6 and

8 respectively and a marginal flange 10 extending from the sides and ends. As clearly shown in Fig. 1 the sections taper gradually in depth from the end 6 toward the end 8.

Formed in the interior of each section are horizontal and vertical partitions 14 and 16 respectively, partition 14 extending completely across the section from side wall to side wall and being arranged within the latter, that is, away from the marginal attachments flanges as clearly shown in Fig. 1. The horizontal partition extends from end to end of the section at an incline with respect thereto, which incline is in accordance with the taper of the section. The partition 14 forms a baffle and is provided with a plurality of transversely arranged openings 17, elongated in the instance shown, which are arranged along one side edge of the baffle or, to be more exact, to one side of the vertical partition 16 (see Fig. 2). The vertical partition extends only partly the length of the muffler section as shown in Figs. 1 and 2 and it defines two horizontally arranged chambers 18 and 20 respectively; chamber 20 being of greater area than chamber 18 to permit expansion of the gases received therein as more clearly pointed out hereinafter. The end 6 of each muffler section is provided with a nipple 22 to which an exhaust pipe is secured.

In assembling the muffler of the present invention, the upper and lower sections A and B are connected together at the attaching flanges thereof by means of suitable fasteners such as bolts 24; the smaller end of the one section being arranged adjacent the larger end of the other section whereby to define a substantially rectangular structure. From an inspection of Fig. 1 it will be apparent that due to the specific construction of the muffler sections, there are provided within the hollow casing spaced parallel baffles which are formed of the two partitions 14. Preferably each partition 14 is provided with an uneven number of openings 17 (5 in the instance shown) whereby when the two muffler sections are assembled the respective openings in the partitions 14 will not be in alignment with each other but will be staggered with respect to each other.

With the muffler sections assembled as shown in Fig. 1, the two nipples 22 are arranged in different elevations; the nipple of the lower section being arranged at a lower 5 elevation than the nipple of the upper section. This provides a construction in which, when the muffler is used with a marine engine, water will be maintained or received in the lower muffler section to provide for the cool- 10 ing of the gases passing through the muffler and also for aiding in the reduction of sound. Due to this "stepped" arrangement of the nipples of each section, the tendency of back- 15 flow of the water from the lower section to the upper section and then into the exhaust pipe connected to the latter is reduced to a minimum.

In use exhaust gases are passed from the exhaust pipe connected to the nipple of the 20 muffler section A into the chamber 20 where they are initially expanded and passed into the chamber 18 of the muffler section A and through the openings in the baffle 14. The gases which have been expanded in the chamber 25 20 are broken up by the baffle 14 of muffler section A and still further broken up by the baffle 14 in the muffler section B and they pass through the openings in the baffle 14 of section B into the chamber 18 of muffler section B and then around the vertical partition 16 of muffler section B into the chamber 20 of said muffler section B where they mingle with the water therein and are still further expanded and reduced in temperature and are 30 exhausted through the nipple 22 connected to the end 6 of muffler section B. Inasmuch as the muffler of the present invention is designed for use with internal combustion engines, including marine engines, the partitions 14 are provided with drain openings 24 to permit draining of any water from the interior of the upper section A into the lower section B.

From the above description it is believed 45 that the construction and operation of the muffler of the present invention will be fully apparent to those skilled in the art to which it appertains. It will be apparent that the muffler shown herein is extremely simple, 50 easy to manufacture and assemble and is formed of two identical parts which are, in effect, complementary whereby a mere bolting together of the two muffler sections will result in the completed structure.

The drawings show one embodiment of the 55 invention but it is to be understood that they are for illustrative purposes only and that various changes in the form and proportions of the device may be made within the scope 60 of the appended claims without departing from the spirit of the invention.

What is claimed is:

1. In a muffler, a pair of similar members 65 adapted to be connected to form a hollow casing, said members each having an in-

clined baffle therein extending from end to end of said members.

2. An exhaust muffler comprising two hollow sections connected together to provide a closed chamber, each of said sections having 70 an inclined baffle therein provided with perforations, the inclined baffles being so positioned in each of said sections as to be parallel with each other in the chamber.

3. An exhaust muffler comprising two connected similar hollow sections each provided with a horizontal partition and an imperforate vertical partition, the horizontal partitions having a plurality of perforations 75 therein arranged at one side of the vertical partitions.

4. An exhaust muffler formed of two similar sections, each tapering in depth from end to end and provided with a perforated horizontal partition inclined in accordance 80 with the taper of the sections whereby when said sections are in assembled position a hollow casing having parallel inclined partitions is provided.

5. An exhaust muffler unit comprising a 90 hollow member tapering in depth from end to end and having a continuous inclined perforated baffle therein extending from end to end, and a longitudinally extending partition at right angles to said baffle and defining 95 two passages.

6. An exhaust muffler unit comprising a hollow member tapering in depth from end to end and having a perforated baffle therein extending from end to end and inclined in accordance with the tapering of said member, said member also having a partition at right angles to said baffle and extending only partly the length of said hollow member.

7. An exhaust muffler unit comprising a 105 hollow member tapering in depth from end to end and having a perforated baffle therein extending from end to end and inclined in accordance with the tapering of said member, said member also having a partition at right angles to said baffle and extending only 110 partly the length of said hollow member, said perforations in the baffle being arranged on one side of said partition.

8. An exhaust muffler comprising a hollow 115 casing having spaced parallel baffle plates therein inclined from end to end of said casing, and partitions arranged in said casing at opposite ends thereof and at substantially right angles with respect to said baffles 120 and each extending only partly the length of said casing, said baffles each having a plurality of perforations.

9. An exhaust muffler comprising a hollow 125 casing having spaced parallel baffle plates therein inclined from end to end of said casing, and partitions arranged in said casing at opposite ends thereof and at substantially right angles with respect to said baffles 130 and each extending only partly the length of

said casing, said baffles each having a plurality of perforations arranged on one side of the partitions.

10. An exhaust muffler comprising a pair of similar sections tapered from end to end and connected to form a hollow casing, each of said sections having an inclined horizontal baffle therein and a vertical partition defining two passages, said partitions extending only partly the length of said sections whereby to provide a communicating area between the two passages, and said baffles having perforations arranged on one side of the vertical partitions.

15. An exhaust muffler comprising a hollow casing having spaced inclined horizontal partitions extending from end to end thereof, a vertical partition in the upper portion of the casing extending from one end partly 20 the length of said casing and defining two passages, one horizontal partition being the base thereof and the portion of the partition forming the base of one passage being provided with perforations, a vertical partition 25 in the lower portion of the casing and extending from the opposite end of the casing partly the length thereof to define spaced passages in the lower portion of said casing, the base of which passages is the other horizontal partition and the portion of the partition forming the base of one of said passages being perforated.

30 12. An exhaust muffler comprising a hollow casing formed of a pair of similar sections each comprising a hollow member tapering from end to end and provided with a horizontal inclined baffle and a vertical partition, the latter defining two passages and extending only partly the length of the member, and said baffle being perforated on one side of the partition.

35 13. An exhaust muffler comprising a hollow casing formed of a pair of similar sections each comprising a hollow member tapering from end to end and provided with a horizontal inclined baffle and a vertical partition, the latter defining two passages and extending only partly the length of the member, and said baffle being perforated on one side of the partition, said members being connected together with the deeper end of one member adjacent the smaller end of the opposite member.

40 14. An exhaust muffler comprising a hollow casing formed of a pair of similar sections each comprising a hollow member tapering from end to end and provided with a horizontal inclined baffle and a vertical partition, the latter defining two passages and extending only partly the length of the member, and said baffle being perforated on one side of the partition, said members being connected together with the deeper end of one member adjacent the smaller end of the opposite member and a nipple at the deeper end of each

member in communication with one of said passages.

15. An exhaust muffler comprising two hollow members tapering in depth from end to end and having the deeper end of one thereof arranged adjacent to and connected with the smaller end of the other, each of said members being identical in form and having a baffle in the interior thereof which is inclined in accordance with the taper of the member, a partition at substantially right angles to the baffle and forming two passages in each member, one of which passages has perforations formed in the baffle, said partitions extending only partly the length of said member, and a nipple at the deeper end of each member whereby when said members are assembled the nipples will be in different horizontal planes.

20 16. In an exhaust muffler, a casing divided horizontally at an incline into upper and lower sections connected together, spaced parallel baffles in the casing, one arranged in each of said sections and provided with perforations, a vertical partition in the upper section joined with the baffle therein, and a vertical partition in the lower section joined with the baffle therein, said perforations being arranged at one side of said vertical partitions.

25 17. In an exhaust muffler, a casing divided horizontally at an incline into upper and lower sections connected together, spaced parallel inclined baffles in the casing, one arranged in each of said sections and provided with perforations, a vertical partition in the upper section joined with the baffle therein, and a vertical partition in the lower section joined with the baffle therein, said perforations being arranged at one side of said vertical partitions.

30 In witness whereof I have hereunto set my hand.

ALBERT W. W. VAN HOORN.
